UNITED STATES PATENT OFFICE.

DANIEL M. MCCOOK, OF MANCHESTER, GEORGIA.

WATER-GAGE.

1,347,701.

Specification of Letters Patent. Patented July 27, 1920.

Application filed October 20, 1919. Serial No. 331,867.

To all whom it may concern:

Be it known that I, DANIEL M. McCook, a citizen of the United States, and a resident of Manchester, in the county of Meriwether 5 and State of Georgia, have invented certain new and useful Improvements in Water-Gages, of which the following is a specification.

My invention relates to water gages, and 10 a purpose of my invention is the provision of a plurality of water gages arranged to give the same indications which can be observed from various angles so that when applied to the boiler of a locomotive, the 15 quantity of water in the boiler can be readily determined by the engineer and fireman without moving from their respective working positions.

It is also a purpose of my invention to 20 provide manually controlled means for supplying steam and water to any one of the gages independently of the others, and means for establishing communication between the gages independently of the steam 25 and water supply to effect a supply from one gage to the other, so that should one of the pipes connected to any gage become disrupted for any reason so as to discontinue the supply of water and steam thereto, the 30 corresponding gage will not be rendered inoperative but can be readily reconnected so that it will again properly function.

I will describe one form and arrangement 35 of gages embodying my invention, and will then point out the novel features thereof in claim.

In the accompanying drawings:—

Figure 1 is a view, showing in front elevation one form and arrangement of gages 40 embodying my invention;

Fig. 2 is a vertical sectional view, taken on the line 2—2 of Fig. 1; and

Fig. 3 is a transverse sectional view, taken on the line 3—3 of Fig. 1.

Similar reference characters refer to similar parts in each of the several views.

Referring specifically to the drawings, and particularly to Fig. 1, G and G' designate generally a pair of gages which are 50 spaced apart in parallelism and are permanently connected at their ends by bridge pieces B and B'. Each gage G or G' comprises, in the present instance, a body 15 having a beveled back, as shown in Fig. 3 55 and a front formed with flanges 16 which

are coextensive in length with the body to provide a seat in which is disposed a glass plate 17. The plate 17 forms a closure for a steam and water chamber 15^a formed in the body 15 at a point midway between the 60 flanges 16, and to prevent leakage between the plate 17 and the walls of the chamber 15^a, packing 18 is interposed between the two, as shown in Fig. 3.

For securing the plate 17 in tight engagement with the body 15, I provide a cover plate 19 preferably formed of brass which is secured to the flanges by means of screws 20. A lip 19^a formed on the inner edge of the cover plate 19 engages the outer side of 70 the plate 17 and thus forces the latter snugly against the packing 18, as will be understood. Graduations are provided on the cover plate for facilitating one in the reading of the gage. 75

As shown in Fig. 3, the gages G and G' are disposed in divergent relation to each other so that the face of one or the other can be easily seen from either side. This is highly desirable when using the gages 80 on a locomotive as the level of the water can be observed by the engineer and fireman without either moving from their positions.

The gages G and G' are adapted to be 85 connected to the same boiler to give a double indication by an arrangement of pipes which supply water to the bottom and steam to the top of the gages for effecting an equalization of pressure in the chambers 90 15^a in the usual manner.

As shown in Fig. 1, W and W' designate a pair of pipes for supplying water to the gages G and G', respectively, from a pipe W² which is connected to a boiler (not 95 shown) and to the pipes W and W' by a branch pipe W³. Drain pipes W⁴ are connected to the pipes W and W' at points below the branch pipe W³ for effecting a drainage of the gages when it is desired. 100 The passage of water to the gages is controlled by manually operated valves V and V', respectively, located within the pipes W and W'; and the exit of water from the pipes W⁴ is controlled by similar valves V². 105

Steam from the boiler is supplied to the gages G and G' through pipes S and S' from a common pipe S² which connects directly to the boiler and to the pipes S and S' through a branch pipe S³. Valves V³ and 110
